[57] CLAIM

The ornamental design for a combined brush handle and back, as shown and described.

DESCRIPTION

FIG. 1 is a top perspective view of a combined brush handle and back showing my new design;

FIG. 2 is a bottom perspective view thereof;

FIG. 3 is a side elevation view thereof;

FIG. 4 is a bottom view thereof;

FIG. 5 is a top plan thereof;

FIG. 6 is a left end elevational view thereof;

FIG. 7 is a right end elevational view thereof.

The broken line disclosure of the bristles in FIG. 2 is for illustrative purposes only and forms no part of the claimed design.
